DESIGN FOR A POKER CHIP OR SIMILAR ARTICLE

Fred William Voges, Ozone Park, N. Y.

Application June 18, 1938, Serial No. 77,928

Term of patent 14 years

To all whom it may concern:

Be it known that I, Fred William Voges, a citizen of the United States of America, residing at 99th Street, near 103rd Avenue, Ozone Park, county of Queens, New York, N. Y., have invented a new, original, and ornamental Design for a Poker Chip or Similar Article, of which the following is a specification, reference being had to the accompanying drawing, forming part thereof.

On the drawing Fig. 1 is a face view and Fig. 2 is an edge view of the poker chip or similar article showing my new design.

I claim:

The ornamental design for a poker chip or similar article, substantially as shown.

FRED WILLIAM VOGES.
